UNITED STATES PATENT OFFICE.

JOHN PENNINGTON, OF CAMDEN, NEW YORK.

UNION UNDERGARMENT.

SPECIFICATION forming part of Letters Patent No. 723,913, dated March 31, 1903.

Application filed September 25, 1902, Serial No 124,832. (No model.)

To all whom it may concern:

Be it known that I, JOHN PENNINGTON, a citizen of the United States, residing at Camden, in the county of Oneida and State of New York, have invented certain new and useful Improvements in Union Undergarments, of which the following is a specification, reference being had therein to the accompanying drawings.

10 My invention relates to an improved union suit or combination-undergarment; and I do declare that the following is a full, clear, concise, and exact description thereof sufficient to enable one skilled in the art to make and 15 use the same, reference being had to the accompanying drawings, in which like letters refer to like parts throughout.

My invention discloses a union suit formed of continuous knitted fabric from the neck 20 to the ankle parts and provided with suitable openings, one of them being at the rear and approximately from the hip portion or waist-line to the crotch portion for the wearer to get into the suit and having provided there- 25 with suitable flaps or attached pieces for completely closing the opening when the garment has been put on.

Union suits have been made of one uncut fabric and then slit or cut, so that the 30 wearer might put them on; but the difficulty has been to provide that opening in a suitable place and of sufficient size and to surround it with suitable and sufficient protection for the wearer, so that the body would 35 remain covered in all its movements and the natural elasticity of the garment and its material be retained, so that the body would not be at all hampered or bound, but at the same time would be fully protected. In seeking 40 to accomplish these essential results flaps of various sizes, fashion, and location have been used without perfectly answering the purpose. With these difficulties and objects in view I have produced a garment shown and 45 described.

Figure 1 is a front view of the garment. Fig. 2 is a rear view, the flaps being closed. Fig. 3 is a like view with the flaps open, and Figs. 4 and 4^a are views of the front and rear 50 flaps of one pair, and Figs. 5 and 5^a those of the other pair.

Referring to the figures more in detail, A

represents the garment, which is knit in one piece. To make the rear opening, I begin at a point *a*, located approximately on the waist-line and above the hip, where I cut the knit fabric of the garment downwardly, transversely, and upwardly along the line *a' a'* to the point *a''*, leaving the flap *B* depending in the back of the original fabric and integral therewith and of sufficient size to form ample covering.

From a point on the front middle line of the garment between the crotch and the waist a cut is made in the garment extending along 65 the medial line to the line *a' a'*, but which is not particularly shown in the drawings, being readily understood. The inner seam of each leg is cut down or left open for a short distance to receive parts *g* and the like part 70 of *H*.

For the purpose of closing the opening after the garment is put on I provide flaps which are attached in the rear and other flaps complementary thereto and attached in front. 75 The outline of the rear flap is substantially as shown by *C*. It has an edge *d d* of an outline to correspond with the vertical and horizontal parts of line *a' a'*, an upper securing edge *e e*, an overlap edge *f f*, and a seam- 80 piece *g*.

The piece *C* is attached to the garment along the edge from which the flap *B* was cut, the vertical and transverse edges of each being joined. The edge *g'* of the seam-piece *g* 85 is sewed in the rear edge of the leg-seam opening from *g'* to *g''*.

H illustrates one of the front flaps opposite to the flap *C*. It has an edge *h h*, substantially straight, from one end of which the 90 edge *h'* retreats at an angle. It also has an overlap edge or portion *j*, which, like the edge *f f* of the back flap, is given the desired extent. The other end of the piece is adapted for binding or sewing onto the front of the 95 garment, the upper ends of the two front flaps being overlapped at their upper end, so as to secure the full benefit of the overlap parts. This piece *H* is attached to the front of the garment, the angular end being attached to the lower end of the front edge formed by the medial cut and the seam-opening and following up the edge *h h* until the other end of the flap is sewed to the body of 100

the garment. The edge h' is sewed to the edge g'' of the corresponding rear flap C. The seam-pieces of the flaps C and H when thus united and sewed into the seam-opening and the medial cut provide the desired fullness in that part of the garment. The main parts of the rear flaps are brought over the flap B, folding over one another and completely close the opening. The overlapping parts of the front and rear flaps render it impossible that the body should be uncovered in any of its movements, yet the pieces are not so full or doubled as to inconvenience the wearer.

15 On the flap B, I provide buttons b and corresponding buttonholes in the flaps C, whereby the garment may be readily fastened and the buttons and holes placed as the wearer may desire.

20 Having described my invention, what I claim as new, and desire to secure by Letters Patent, is—

1. A union garment formed with a rear opening approximating the outline of the seat 25 of the garment, the flap formed by said cut remaining integral with the garment, and with a front opening, and with openings in the leg-seams, and flaps to cover the front

opening and rear opening, said flaps having extensions secured to the leg-seam edges, the extensions of the respective back and front flaps being secured to each other, as and for the purposes stated.

2. A union garment formed with a rear opening by cutting on the outline of the seat, 35 the flap formed by said cut remaining integral with the garment and coextensive with the opening, and overlapping flaps secured to the garment to cover the opening, each of said flaps having an extension secured in the 40 leg-seam of the garment.

3. A union garment formed with a rear opening approximating the outline of the seat, overlapping flaps secured to opposite sides of the outline edge of the opening, extensions 45 depending from said flaps secured in opposite leg-seams adjacent the crotch of the garment, and suitable fastening devices to secure the flaps in overlapped position to the garment.

In testimony whereof I affix my signature in presence of two witnesses.

JOHN PENNINGTON.
